 Delaware

Application April 9, 1943, Serial No. 482,435

5 Claims. (Cl. 202—39.5)

1

This invention relates to a method of using a selective solvent for hydrocarbons, particularly aliphatic unsaturated hydrocarbons, wherein dry solvent is introduced at the top of the absorption column, water near the bottom of the column, and the hydrocarbon feed at some point intermediate to the introduction of the solvent and the bottom of the tower. More specifically, it relates to the use of furfural in the manner described for the recovery of butenes or butadiene. This method of using furfural permits utilization of the absorptive capacity of dry furfural and in the colder sections of the absorption tower it decreases the possibility of the formation of two liquid phases consisting of solvent and hydrocarbon.

Dry furfural has higher absorptive capacity for hydrocarbons than furfural containing small percentages of water. However, in the stripping of dry rich furfural to remove the absorbed hydrocarbons, the temperature of operation is determined by the boiling points of the furfural-hydrocarbon mixtures at the given pressures. In the case of butene or butadiene recovery wherein a C₄ fraction is selectively extracted with furfural, it is desirable to maintain the pressure high enough in the stripping column that the thus recovered hydrocarbons can be readily condensed to a liquid by ordinary cooling means. Consequently, the operating temperatures are necessarily relatively high. When small percentages of water are used, these temperatures are appreciably reduced and the resultant temperature reductions reflect the advantage of lowered furfural and/or other polymer, gum, and coke formation, lowered heat loads, and less heat transfer equipment.

The extent to which the incorporation of water in furfural effects a lowering of the boiling point varies with the amount of water used. The addition of up to 3 or 4 per cent by weight of water causes a very marked decrease in the boiling point of furfural. For additional small percentages the boiling point is depressed considerably less. This is shown by the following tabulation:

B. P. °F.

Furfural	323
Furfural+1% water by weight	296
Furfural+2% water by weight	229
Furfural+3% water by weight	220
Furfural+4% water by weight	215
Furfural+6% water by weight	211
Furfural+8% water by weight	209.5

The boiling point approaches a minimum of 208°

2

F. It can be seen that, ordinarily, little advantage is to be gained by using an amount of water greater than 4 to 8 per cent. The upper limit of water added will usually be governed by the lowest temperature in the absorbing and stripping system. For example, in a column using furfural-water as a selective solvent for butadiene, operated at a pressure of 65 pounds per square inch absolute, the kettle temperature is 250° F., while the temperatures near the top in the absorption sections are about 110° F. Therefore, it is not desirable to use more than 6.5 per cent by weight of water in furfural, which is the limit above which two liquid phases would appear at 110° F.

15 The selectivity of furfural for hydrocarbons is not greatly influenced by small percentages of water. As an example, the following table shows the selectivity of furfural and furfural-water for butadiene over butene-1, where the selectivity is measured by the relative volatility of butene-1 relative to butadiene in furfural and furfural-water solvents. The relative volatility is defined as $(y_{HB})/(x_{Hb})$ where y_H and x_H are mol fractions of an individual hydrocarbon (in this case butene-1) in vapor and liquid, respectively, and y_B and x_B are the mol fractions of butadiene in vapor and liquid, respectively.

20 Selectivity of furfural and furfural-water for butadiene over butene-1; fifty pounds per square inch gage pressure

10	do	1.598
45	do	1.666
11	do	1.725
	Average	1.678

50 As previously pointed out, the absorptive capacity of furfural for hydrocarbons is affected by the amount of water in the furfural while the selectivity is not appreciably changed. The absorptive capacity of furfural is decreased as the amount of water added is increased. Consequently, there is a possibility for the separation of two

liquid phases should any portion of an absorption system containing rich solvent and the proper amount of water operate at a relatively low temperature, such as is frequently obtained in the top part of an absorption column. The relative absorptive capacities of dry furfural and furfural containing small percentages of water is shown by the following tabulation wherein is given the maximum weight per cent of liquid n-butane, butene-1, and butadiene absorbed by furfural or 10 furfural-water mixtures without the separation of two liquid phases. These data are given for several different temperatures:

compositions are such to make likely separation of two liquid phases.

In the latter of the preceding tabulations, the solubility of C₄ hydrocarbons in dry furfural and in furfural containing small percentages of water was shown. Reference to this table shows that the solubility of the hydrocarbons increases in the order of n-butane, butene-1, and butadiene. The volatility of these hydrocarbons in dry furfural or in furfural containing water is in the reverse order of their solubility. That is, n-butane is the most volatile, butene-1 next most volatile, and butadiene the least volatile. Therefore, in the

Solubility of liquid C₄ hydrocarbons in liquid dry furfural and in liquid furfural containing water

¹ Water phase separates.

² May be water phase separation.

This invention provides a means whereby the advantages of both dry furfural and furfural with small percentages of water may be utilized to the essential exclusion of the disadvantages experienced from the use of dry or wet furfural alone by conventional means.

Conventionally, selective solvents, either dry or with small amounts of water dissolved therein, are introduced near the top of an absorption column. The hydrocarbon stream to be purified is introduced at some lower point such as the middle. The column is usually provided with a re-boiler or its equivalent to supply stripping vapor in the bottom section of the tower in order to strip the less selectively absorbed hydrocarbons from the solvent in the lower portion of the tower thereby separating them from the more selectively absorbed constituents. The rich solvent is then stripped of the remaining absorbed constituents in a second column in order to effect their recovery. In the case of furfural, as pointed out, the use of dry solvent makes necessary the use of relatively high operating temperatures in the reboiler of the extraction tower and of the stripper with resultant furfural decomposition, polymer and coke formation, etc. The use of wet furfural in the same manner results in greatly decreased operating temperatures but decreases the absorptive capacity of the solvent, thereby requiring higher recirculating rates than with dry furfural. Also, it may result in the separation of two liquid phases in the absorption system. In my invention, I propose to take advantage of the desirable features of wet and dry furfural as a selective solvent to the essential exclusion of the undesirable features of each by introducing dry furfural near the top of an absorption column, hydrocarbon vapors at a lower point in the column, and small quantities of water at some intermediate point in the column, preferably below the point of introduction of the hydrocarbon vapors. By proper spacing of the points of introduction of water and hydrocarbon, the hydrocarbon stream will be contacted with substantially dry furfural in those sections of the column where low temperatures and/or hydrocarbon

absorbing tower the hydrocarbon of the least solubility will be present in the greatest concentration at the top of the tower, where the temperature is the lowest. As the hydrocarbon rich furfural flows down the column, it slowly increases in temperature and comes in contact with hydrocarbon compositions permitting greater concentrations of water in the furfural without danger of separation of two liquid phases. When tolerance of the liquid mixture for water is great enough, the desired quantity of water may be added as steam or liquid. Consequently, this arrangement results in a solvent possessing high absorption capacity throughout the tower while at the same time realizing the advantages of both dry furfural and furfural containing small percentages of water.

Using furfural in the manner described makes it necessary to dry or partially dry the solvent before it is recirculated to the absorption zone. This may be done by fractionation. Furfural forms a minimum boiling type azeotrope with water. Since furfural containing only small percentages of water is used, the furfural-water mixtures are therefore on the water-in-furfural side of the vapor-liquid boiling point composition curve. Therefore such mixtures may be readily fractionated into pure furfural and the furfural-water azeotrope. In such a fractionation, dry furfural is the bottom product and the azeotrope the overhead product. By sufficiently cooling the overhead product, separation into two liquid phases is obtained, one phase rich in furfural and the other rich in water. The furfural-rich phase may be refluxed to the fractionator for additional fractionation. The water-rich phase, which contains about 6-8 weight per cent of furfural at 100° F. may be recycled to the absorption zone as the source of water to be injected at a low point in the absorption zone as previously described. The furfural fractionator accumulator is preferably provided with a vent for venting any hydrocarbon gases which might otherwise accumulate therein because of imperfect stripping of the rich furfural. If desired, these gases may be vented to a compressor and returned to the rich furfural stripping column. In the case of recov-

ery of butadiene with furfural, these vent gases will be primarily butadiene and may be merged with the butadiene product effluent from the stripper.

As previously mentioned, it is desirable to maintain the pressures in the absorption and stripping zones sufficiently high that the recovered hydrocarbon gases can readily be condensed by ordinary cooling means. The furfural fractionator, however, need not be run at such pressures. It may be run at substantially atmospheric or even under vacuum. Atmospheric pressure or a slight positive pressure may be preferable in order to insure keeping air out of the system. The oxygen of the air tends to promote furfural polymer formation. In general, the temperature in the bottom of the furfural fractionator under atmospheric pressure will not be much greater than the temperature existing in the reboiler section of the stripping zone containing furfural and water under the pressures required for the overhead gas products to be readily condensed by ordinary cooling means.

In most instances it is not necessary to completely dry the furfural. From a temperature standpoint, usually about 4 to 8 weight per cent of water is desirable in furfural used as a selective solvent for hydrocarbons. Drying such mixtures to about one weight per cent water greatly increases the absorptive capacity of the solvent, but it is necessary to dry the furfural only to the extent required to prevent two liquid phase separation under the conditions of operation of the absorption zone. Since this is true and since the pressures maintained in the absorption and stripping zone are usually relatively high, the furfural in many cases may be sufficiently dried by simply flashing the lean furfural from the absorption and stripping system to atmospheric pressure. If this is done, the furfural fractionator may be replaced with a flash tank. The overhead and bottom products from the flash tank may be handled in the same manner as with a fractionator, except that the furfural-rich phase resulting from the condensing and cooling of the overhead product need not be refluxed to the flash tank, but may be either withdrawn from the system, added to the bottom product from the flash operation and returned to the absorption zone, added to the feed to the flash tank, or added to the feed to the rich solvent stripper, depending on ultimately desired composition and required heat balance.

The drawing is a diagrammatic representation of one embodiment of the invention. Vaporized hydrocarbon feed is introduced into the extraction column 16, through conduit 1, at about the middle. Dry furfural is introduced near the top of the column on the top tray through conduit 13. The dry furfural flows downwardly countercurrent to the uprising vaporized feed. Water is introduced into column 16 near the bottom through conduit 15 and through at least one of conduits 23, 24, and 25. Reboil heat is supplied to the column at the bottom to remove the less selectively dissolved hydrocarbons. These hydrocarbons pass upwardly through the column and are removed through line 2. At least a portion of the overhead product is condensed and refluxed to the absorber (means not shown because conventional). The furfural-water mixture rich with the selectively absorbed hydrocarbons leaves column 16 as the bottom product through conduit 3 to enter stripping column 17. Reboil heat is supplied at the bottom of the stripping column to

desorb the hydrocarbons in the rich furfural-water mixture. The desorbed hydrocarbons are withdrawn overhead through conduits 4 and 8. A portion of the desorbed hydrocarbon overhead product is condensed and refluxed to the stripper (means not shown). The desorbed hydrocarbons may then be further purified, stored, used in other processes, etc. The lean furfural-water mixture leaves stripping column 17 by means of conduit 5 and enters fractionator 18 where it is fractionated into substantially dry furfural and the furfural-water azeotrope. The dry furfural is removed as the bottom product through conduit 11 and returned to the absorption zone through conduit 13. Conduit 12 connecting with conduits 11 and 13 is provided for adding fresh dry furfural from an external source in order to permit replacing any lost from the system. The furfural-water azeotrope is removed overhead from column 18 through conduit 6 and cooler 19 to enter accumulator 20. Cooler 19 is operated in such a way that the azeotropic mixture is condensed and cooled sufficiently that two liquid phases form in accumulator 20. One phase, the lower one, is a furfural-rich phase which may be refluxed in total or in part to column 18 through line 10. The other phase is a water-rich phase which is returned to absorption column 16 through conduits 9 and 15. Conduit 14 connecting with 9 and 15 is provided for adding water from an external source to replace any lost from the system. Accumulator 20 is provided with a vent line 7 for venting any absorbed hydrocarbons retained in the lean furfural and subsequently desorbed in fractionator 18 to accumulate in accumulator 20. The vented hydrocarbons may be sent to disposal or may be compressed and added to the overhead product from stripper 17. The vent gases from this accumulator will consist primarily of the same hydrocarbons as those in the overhead product from stripper 17.

In order to prevent the accumulation of contaminants in the furfural, such as heavy polymers of furfural and hydrocarbon polymers, it may be necessary to subject the bottom product of stripper 17 to a purification step (not shown). This may be done either batchwise or continuously by any satisfactory means, for example, a method such as that disclosed in the copending application of Buell et al. Serial No. 460,004, filed Sept. 28, 1942. The thus purified furfural may then be fed to column 18 for drying.

Example

As an example of the operation of my invention, an unsaturated C₄ petroleum fraction, from a source not shown, containing about 3 parts propane, 63 parts butadiene, 13 parts butene-1, 5 parts isobutylene, 13 parts butenes-2, and 3 parts n-butane along with a trace of vinyl acetylene and C₅ and heavier was charged to absorber 16 through line 1 located near the middle of absorber 16.

Lean substantially dry furfural from fractionator 18 was introduced into absorber 16 through line 13, near the top of the absorber. Enough liquid water from accumulator 20 was introduced into absorber 16 near the bottom by means of lines 9 and 15 to give a resultant furfural-water mixture containing about 5 per cent by weight of water. Rich furfural-water mixture containing 4 parts butadiene and 0.3 parts of butenes-2 along with a trace of C₅ and heavier and vinyl acetylene was withdrawn from the bottom of absorber 16 through line 3 and charged to strip-

per 17. The product withdrawn from the top of absorber 16 through line 2 contained about 45 parts of butene-1, 10 parts propane, 17 parts isobutylene, 17 parts butenes-2 (mostly low boiling), and 11 parts butane. The absorber was operated at a pressure of 65 pounds per square inch absolute, reflux ratio of 16:1, top temperature of 80° F. and bottom temperature of 240° F.

Stripper 17 was operated at a pressure of 65 pounds per square inch absolute, reflux ratio 1:1, top temperature of 103° F. and bottom temperature of 300° F. Lean furfural-water mixture containing about 0.1 per cent C₄'s was withdrawn from the bottom of the stripper through line 5 and charged to fractionator 18. The stripper overhead product, consisting of 93 parts butadiene and 7 parts of butenes-2 along with traces of isobutylene, butene-1, C₅ and heavier, vinyl acetylene, and furfural, was charged to a fractionator (not shown) through lines 4 and 8 for the recovery of essentially pure butadiene.

In fractionator 18, the furfural-water mixture was fractionated to obtain substantially dry furfural as a bottom product and furfural-water azeotrope as the top product. The furfural-water azeotrope was removed overhead from fractionator 18 through line 6 into condenser 19 and the resulting condensate introduced as a liquid into accumulator 20 where two liquid phases were allowed to separate. The bottom layer, the furfural-rich phase, was totally refluxed to column 18 by means of line 10. The top layer, water-rich phase, was recycled to absorber 16 by means of lines 9 and 15 to supply the water required near the bottom of absorber 16. Accumulator 20 was also equipped with vent line 7 for venting absorbed hydrocarbons not completely stripped from the furfural-water solvent in stripper 17. This vent stream was compressed to substantially the same pressure as the overhead gases from stripper 17 by means of compressor 21, and added to the overhead stream from stripper 17. The bottom product of fractionator 18 was removed through lines 11 and 13 and recycled to the top portion of absorber 16. Fractionator 18 was operated at essentially atmospheric pressure, top temperature of 208° F. and bottom temperature of 323° F.

It is to be understood that instead of water in the liquid form I may introduce steam as the source of water to the absorber 16. This steam may conveniently be formed by vaporizing the water recycle from accumulator 20 by passing it via line 21 through vaporizer 22 whence the steam thus formed is introduced into the absorber 16 via line 15 and preferably via line 23 into the reboiler section thereof. Makeup steam from an extraneous source may be supplied for this purpose via line 26.

Use of steam in preference to water is advantageous in that introduction of steam supplies not only the desired proportion of water to reduce the boiling point of the furfural but also a large quantity or under optimum conditions all of the heat required for the operation of the absorber. While it is desirable to introduce such steam into the reboiler section of the absorber, it is to be understood that it may be introduced at a point further up in the column. Fouling of the reboiler which supplies all the heat when water is used is responsible for considerable operating difficulties. However, these difficulties are minimized by

introducing steam which supplies the needed water and at least a part of the heat required in the absorber 16.

As used herein and in the appended claims the "water" is intended to designate either liquid water or steam unless otherwise specified.

Reference is made under Rule 43 to my prior and copending application, Serial No. 438,844, filed April 13, 1942, which discloses and claims the use of furfural containing a minor proportion of dissolved water in the extraction of aliphatic unsaturated hydrocarbons.

I claim:

1. In the process of concentrating an aliphatic unsaturated hydrocarbon from a hydrocarbon mixture containing the same and other close boiling more saturated hydrocarbons wherein a stream of said hydrocarbon mixture is introduced at an intermediate point in an absorption column, furfural containing small amounts of water is introduced near the top of said column and serves as selective solvent for the unsaturated hydrocarbon, the hydrocarbon mixture is subjected to combined simultaneous extraction and rectification in said column, hydrocarbon vapors depleted in the unsaturated hydrocarbon are withdrawn overhead, a kettle product of furfural rich in unsaturated hydrocarbon containing substantially all water introduced into said absorption column is withdrawn from the bottom of the column and the unsaturated hydrocarbon is stripped from the bottoms product in a stripping zone that improvement which comprises maintaining the water content of the furfural introduced as selective solvent into the top of the absorption column at sufficiently low level to prevent separation of two liquid phases in the upper portion of the absorption column, introducing water into a plurality of vertically spaced points in lower portion of the absorption column and controlling the amount of water so introduced so that the proportion of water present at any specified point within the column is less than the proportion of water which would cause separation of two liquid phases at the same specified point and so that the proportion of water contained in the furfural in the upper portion of the column is less than such proportion in the lower portion of the same column, and so that said water content progressively increases toward the bottom of said column, whereby high absorption efficiency toward unsaturated aliphatic hydrocarbons is maintained in the furfural in the upper portion of the column while the boiling point of the furfural in the lower portion of the column is lowered.

2. The process of claim 1 wherein the hydrocarbon mixture is a mixture of aliphatic C₄ hydrocarbons.

3. The process of claim 1 wherein the hydrocarbon mixture is a mixture of aliphatic C₄ hydrocarbons and wherein the unsaturated hydrocarbon is butene.

4. The process of claim 1 wherein the hydrocarbon mixture is a mixture of aliphatic C₄ hydrocarbons and wherein the unsaturated hydrocarbon is butadiene.

5. The process of claim 1 wherein said water is in the form of steam and is introduced in the reboiler section of said column.

KARL H. HACHMUTH.
